UNITED STATES PATENT OFFICE.

SAMUEL GEORGE WEBB, OF ASBURY PARK, NEW JERSEY.

DESIGN FOR AN ADVERTISING BOOTH.

Application filed August 17, 1927. Serial No. 23,113. Term of patent 14 years.

To all whom it may concern:

Be it known that I, SAMUEL GEORGE WEBB, a citizen of the United States of America, residing in Asbury Park, in the county of Monmouth, in the State of New Jersey, have invented a new, original, and ornamental Design for Advertising Booths, of which the following is a specification, reference being had to the accompanying drawing, forming a part thereof.

Fig. 1 of the drawing shows a view of the front and side of a booth embodying the new design, and Fig. 2 shows a view in perspective of the opposite side and rear of the booth shown in Fig. 1.

I claim:

The ornamental design for an advertising booth, as shown.

S. GEORGE WEBB.
